UNITED STATES PATENT OFFICE.

ROBERT HOPE-JONES, OF NORTH TONAWANDA, NEW YORK, ASSIGNEE TO THE
RUDOLPH WURLITZER MANUFACTURING COMPANY, OF NORTH TONAWANDA,
NEW YORK, A CORPORATION OF NEW YORK.

ELECTROPNEUMATIC ORGAN-VALVE.

1,201,585.

Specification of Letters Patent. Patented Oct. 17, 1916.

Application filed July 15, 1910. Serial No. 572,082.

To all whom it may concern:

Be it known that I, ROBERT HOPE-JONES, a subject of the King of Great Britain, residing at North Tonawanda, in the county 5 of Niagara and State of New York, have invented certain new and useful Improvements in Electropneumatic Organ-Valves; and I do hereby declare the following to be a full, clear, and exact description of the 10 same, reference being had to the accompanying drawings, forming a part of the specification, and to the reference-numerals marked thereon.

My present invention has for its object to 15 provide an improved form of valve adapted particularly to be used in organ building, its construction being such that when so employed it may be used as a primary valve for controlling the speaking of the various organ pipes.

In connection with a valve of this character my invention has for its further object to provide an electromagnetically-operated valve in which the casing and magnet are 25 combined, the whole being small in size although provided with air passages of ample area to effect a quick response of the air in the channels controlled by the valve.

My invention also has for its object to 30 provide certain improvements and arrangements of parts enabling the valve and its magnet to be readily disconnected from the wind trunk or similar portion of the organ to which it is attached, as well as to provide 35 for convenient access to the interior of the valve casing itself.

To these and other ends the invention consists in certain improvements and combinations of parts all as will be hereinafter more 40 fully described, the novel features being pointed out in the claims at the end of the specification.

In the drawings.—Figure 1 is a diagrammatic view of an organ action including a 45 valve constructed in accordance with my invention, and illustrating its arrangement and operation in conjunction with the parts of an organ with which it may be associated; Fig. 2 is an enlarged detail view showing the valve casing in section; Fig. 3 is a bottom plan view; Fig. 4 is a sectional view taken on the line 4^x—4^x of Fig. 3; Fig. 5 is

a plan view of the inner side of the upper portion of the valve casing, and Fig. 6 is a similar view of the lower part of the casing. 55

Similar reference numerals in the several figures indicate similar parts.

Valves constructed in accordance with my invention, while capable of being used for other purposes, are adapted particularly to 60 fulfil the function of primary valves which are used for venting the small air passages or channels controlling the secondary valves, which, in turn, cause the organ pipes to speak, and in Fig. 1 I have shown a valve 65 constructed in accordance with my invention arranged in operative position in relation to the co-operating parts of an organ mechanism. In this figure of the drawing is shown the wind chest 1 containing the chamber 2 to which air is supplied under pressure from any convenient source. One of the simpler forms of secondary valves, indicated by 3, is also shown operated by the rod 4 connected to the bellows 5 located in the 70 chamber 2, which is operated by the air pressure in the latter when the controlling passage 6 is opened to the atmosphere. The passage 6 is frequently formed in the walls of the wind chest, as shown, and terminates 75 in the port 7 communication between which and the aperture or port 8, leading from the chamber 2, is governed by the valve mechanism, as will be described more in full hereinafter. The valve being electromagnetically 80 operated is arranged in a circuit, which is closed when the key or manual 9 is depressed, and in Fig. 1 I have also shown the circuit diagrammatically as composed of the wires 10 and 11 together with the battery 12 or other source of current, and the circuit contacts 13 which are closed when the key is depressed.

In illustrating the present embodiment of my invention I have shown a valve comprising 85 a casing composed of an upper section 14 and a lower section 15, the latter being detachable from the former and held in proper position thereon by dowel pins 16. The separable half sections of the casing are 100 preferably made of cast metal. The upper section of the casing is attached permanently to an electromagnet having the parallel pole pieces 17 and 18, the extremities of which

project through and are flush with the inner face of the part 14. The pole pieces are provided with the usual windings 19 which are made comparatively small in diameter 5 in order to permit the pole pieces to be brought close together so that the width of the magnet will be somewhat less than an inch, the desired magnetic effect being obtained by making the pole pieces of the required length. This detail in the construction of the magnet possesses its advantages because a complete organ necessarily requires the use of several hundred primary valves, and these must all be arranged in 15 the wind chests, as shown in Fig. 1, and the size of the wind chests being frequently determined by other limitations which it is necessary to take into consideration in organ building, it is important that the primary valves be made small and compact.

The valve casing is provided with a chamber or windway, formed by a recess 20 in the lower section 15 which normally connects the passage 6 and the aperture 8, one end 25 of the windway or chamber having the passage 21 leading laterally through the upper section 14 and registering with the port 7. One of the walls of said passage is inclined, as shown, to permit the free ingress and 30 egress of the air therethrough as the wind passes into the channel 6 from the chamber 2, or moving in the reverse direction passes outwardly through the windway in the valve casing to the atmosphere. The valve is applied in position on the face board 1^a of the wind chest, which is provided with the aperture 8 of sufficient diameter to accommodate the magnet, and also provide ample space for the circulation of the wind, the lower 35 end of said aperture being covered by the valve casing in which is provided the inlet port 22 located between the pole pieces and affording communication between the interior of the wind chest and the valve casing. The desired area in the port 22 is obtained by making the lateral and end walls thereof curved, as shown, so that its width at the ends is greater than at the center. The object in making the port in this shape 45 is to provide it with a maximum area yet leaving sufficient material between the pole pieces of the magnet and the walls of the port so as not to weaken the casing. A port of this shape also distributes the pressure 50 evenly on the valve head and being located between the pole pieces the pressure will be exerted on the head centrally.

The movable member of the valve is made of a small iron disk or armature 23 located 55 directly beneath the pole pieces of the magnet and provided upon its upper surface with a thin cover of paper or other material which will prevent intimate contact between it and the ends of the pole pieces and thus 60 prevent the disk from being retained by the

residual magnetism of the magnet, which on account of the light weight of the disk might cause it to adhere to the pole pieces or to render the disk sluggish in its action in returning to normal position when the magnet 70 is deenergized. The movable member of the valve is held in its proper position relatively to the pole pieces by a plurality of small posts or pins 25 carried on the lower section 15 of the valve casing and forming means 75 for centering the disk. The movable member or disk is normally seated in the position shown in Fig. 2 closing the outlet passage and controlling the passage of air through two curved or segmental apertures 80 or ports 26. The walls of the latter taper inwardly, as shown in Figs. 3 and 4, and terminate in the seats indicated by 27 formed on the faces of the bosses or nipples projecting upwardly from the bottom of the recess 85 20 which are of sufficient height to support the disk 23 centrally between the upper and lower walls of the chamber 20 so that the air admitted into the casing through the port 22 under pressure, will as nearly as 90 possible, exert an equal influence upon each side of the disk and thus reduce to a minimum the work required of the magnet. It is to this end that the apertures 26 are made in the segmental shape illustrated, as I have 95 found in practice that this form permits providing the valve seat with passages of sufficient area to vent the relief channel 6 satisfactorily without causing such a great difference between the air pressure exerted 100 on opposite sides of the disk as to require the use of a strong magnet to lift it from its seat.

The outlet apertures 26 are arranged symmetrically at opposite sides of a line extending at right angles to the center line of the port 22, and are curved and located with their central points adjacent, an advantage being obtained by this arrangement in that the disk 23 is so nicely balanced that both 110 when attracted by the pole pieces and released therefrom it simultaneously opens and closes both of the valve seats instead of having a tendency to tilt thereon, and thus imperfectly control the opening and closing 115 of the ports. The curving of the ports 26 and positioning them as shown provides means whereby the air currents may impinge on the disk in transverse lines falling near the center of the disk and arrangement of parts which not only adds to its free action, as mentioned above, but also assures its 120 properly seating although it is loosely retained between the pins 25.

In order to prevent the entrance of dust or 125 other foreign particles which might interfere with the operation of the valve, there is inserted between the sections of the casing a screen, and for this purpose I preferably employ a foraminous fabric, such as chiffon or 130

bolting cloth, indicated by 28, pasted on the face of the upper section 16, covering the passage 21 and port 22.

The valve structure is preferably detachably connected to the wind trunk in the position shown in Fig. 1, by means of screw hooks 29, the heads of which may be rotated into engagement with the outer face of the section 15 of the casing and when in this position hold the parts of the casing together, and the latter as a whole being tightly locked in engagement with the face board 1^a of the wind chest.

In order to economize space and permit the adjacent valve casings to be arranged closely together as well as to accurately center each of the casings, I provide the edges of the valve casing with notches receiving the bodies of the fastening devices 29. These notches I prefer to locate at diagonal corners of the valve casing, as indicated at 30, making them of sufficient depth so that the shanks of the screw hooks will lie within the rectangular outline of the casing. By this arrangement only two hooks are devoted to a single valve structure and in practice when these are arranged side by side any one of them may be detached by revolving its fastening devices the heads of which will then extend outwardly without interference with the casings of the adjacent valves.

A valve constructed in accordance with my invention is simple in construction, possesses few parts, and the sectional casing made in the form shown is particularly adapted to be made of cast metal. The means employed for attaching the casing to its support or the coöperating part of an organ facilitates its ready attachment and removal and the inspection of the valve disk. Moreover the arrangement of the parts as described and the disposition of the ports in the chamber or windway provides an extremely sensitive and quickly operating valve.

I claim as my invention:

1. In a primary valve for musical instruments, the combination with a casing composed of separable sections having a chamber between them and an electro-magnet comprising pole-pieces located in one section, the latter being provided with a port located between said pole pieces, of bosses within the chamber on the other section of the casing having apertures, and forming a plurality of valve seats extending across the port and having their ends extending beyond the sides thereof and a metallic

member normally closing the aperture and adapted to be attracted by the magnet to open the latter and close the port.

2. In an electromagnetically operated valve, the combination with a casing composed of upper and lower sections, an electromagnet having pole pieces secured in the upper section, the latter being provided with an aperture located between the pole pieces, and the lower section being recessed to form a chamber, of bosses arranged in the recess of the lower section, the latter being provided with apertures extending through the bosses, a movable valve member coöperating with the faces of the bosses to normally close said apertures last named and pins spaced about the bosses and forming a retaining cage for the member.

3. The combination with a valve casing composed of separable sections provided with a chamber, one of said sections having an outlet passage for the chamber and an inlet port, the other section being provided with an outlet port, of a foraminous fabric located between said sections, a movable valve member coöperating with the outlet port and an electromagnet for operating said member.

4. As an article of manufacture a valve mechanism comprising a casing composed of two separable half sections of cast metal and provided with a chamber having an opening leading through one of the sections, one of the latter being provided with an inlet port, the other having an outlet port, an electromagnet having its pole pieces secured in the first mentioned section, and a movable member coöperating with the magnet and controlling the passage of air through both ports.

5. The combination with a support and a valve mechanism comprising a rectangular casing having notches in its diagonal corners, of fastening members each comprising a shank rotatably connected to the support and a head thereon movable into and out of engagement with said casing by rotation of the shank, said shanks occupying said notches and being arranged within the dimensional lines of the casing, whereby a plurality of such casings may be placed in contact with one another side by side or end to end.
